BOOK AND MAGAZINE HOLDER
Bruce L. Clayton, 1501 Bellevue St., Greensboro, N.C.
Filed May 5, 1961, Ser. No. 107,979
3 Claims. (Cl. 45—85)

This invention relates to improvements in book and magazine holders that are adapted to retain a book or magazine in any inclined position that is convenient for a reader whether they are reading or copying from the book or magazine being so retained by the book and magazine holder.

An object of this invention, therefore, is to provide an improved book and magazine holder that is susceptible of being adjusted so that the book and magazine holder may retain books and magazines of varying sizes, as well as susceptible of being adjusted so that the angular inclination of the book or magazine may be adjusted to conform with the angle of vision of the reader.

Another object of this invention is to provide a book and magazine holder that will retain the book or magazine in open position so that the reader's hands may be free at all times to either copy from the book and magazine or perform other feats while reading or studying from the book or magazine.

A further object of this invention is to provide a book and magazine holder that may be used by a reader when in a sitting position or when lying down.

A still further object of this invention is to provide a book and magazine holder that is simple in construction, efficient in operation and inexpensive to manufacture.

With the above and other objects and advantages in view, the invention consists of the minor details of construction, arrangement and combination of parts more fully hereinafter described, claimed and illustrated in the accompanying drawings, in which:

FIG. 1 is a front elevational view of a book and magazine holder embodying the invention;

FIG. 2 is a vertical sectional view on the medial line 2—2 of FIG. 4;

FIG. 3 is a rear elevational view of FIG. 1;

FIG. 4 is a horizontal sectional view; and

FIG. 5 is a rear elevational view of the upper support or page retaining member of the book and magazine holder embodying the invention.

Referring more in detail to the drawings, wherein like parts are designated by like reference numerals, the reference numeral 10 is used to generally designate a book and magazine holder embodying the invention.

The book and magazine holder 10 comprises an upper body plate member or base 11 which has a straight bottom edge 12, straight side edge portions 13 and 14 and upwardly and converging inclined top edge portions 15 and 16 that terminate in an apex portion 17. Extending at right angles to and forwardly of the body plate member 11 and integral therewith is a lower book support member or flange 18. The lower support member 18 has rounded corner portions 19 and 20, as clearly shown in FIG. 4, and extending longitudinally of and adhesively secured to the rear surface of the lower support member 18 and bottom edge 12 is a narrow elongated scuff member 21 that prevents the bottom edge portion 12 of the book and magazine holder 10 from marring or scratching any surface upon which it is placed.

Punched from and extending rearwardly of the plate member 11 are a pair of horizontally aligned apertured ears 22 and 23. The ears 22 and 23 are positioned on opposite sides of the vertical medial line of the plate member 11 and are equally spaced therefrom. Also punched from and extending rearwardly of the plate

2

member 11 is a third apertured ear 24 to which is secured one end of a chain member 25.

Vertically aligned openings are positioned on the vertical medial line of the body plate member 11 to receive a short upper bolt member 26 and a slightly longer lower bolt member 27 which extend into upper and lower elongated slots 28 and 29 that are provided in a channel-shaped support member 30. The support member 30, at its upper end, is secured to an intermediate plate member 31 of an upper support or page holder 32 and the intermediate plate member 31 has a right angularly disposed longitudinally extending integral flange 33 that is in contact with, when at rest, the longitudinally extending medial line of a substantially inverted U-shaped top plate member 34 of the upper page holder 32. Member 34 includes a web extending across the top of the intermediate plate member 31. The support member 30 is secured to the intermediate plate member 31 by rivets 35 and the flange 33 of the intermediate plate member 31 has sliding contact with the top plate member 34.

The web of the top plate member 34 has a vertically depending longitudinally extending integral rear flange 36 and a vertically depending longitudinally extending integral front flange 37 that is wider transversely thereof than the rear flange 36.

The front flange 37, the intermediate plate member 31 and the rear flange 36 are provided with transversely aligned, longitudinally spaced openings in which are positioned transversely extending pin members 38 and 39. Each of the pin members 38 and 39 is provided at its opposite ends with enlarged heads 40 and 41 to prevent disengagement of the pins 38 and 39 from the front flange 37, the intermediate plate member 31 and the rear flange 36. Positioned on each of the pins 38 and 39 intermediate of the front flange 37 and the intermediate plate member 31 is a limiting or stop member 42 and positioned on each of the pins 38 and 39 intermediate of the rear flange 36 and the intermediate plate member 31 is a spring 43. The intermediate plate member 31 is thus stationary to permit forward and rearward movement of the front and rear flanges 36 and 37 against the tension of springs 43, the stop members 42 limiting or stopping the movement of the front flange with respect to the intermediate plate member. This arrangement permits the top page holder 32 to adjust itself automatically by tilting in a plane normal to the intermediate plate member 31. Thus, when the reader has reached the middle of the book as shown in FIG. 4, the front flange 37 will be parallel to the intermediate plate. However, at the beginning of the book it will be tilted toward the earlier pages to accommodate the unbalanced arrangement of pages. Toward the end of the book the holder will be tilted in the opposite direction, of course. This adjustment occurs automatically to some slight effect as each page is turned.

With the support member 30 positioned on bolts 26 and 27 by reason of the elongated slots 28 and 29, a resilient washer 44 is positioned on the lower bolt member 27 and then an elongated stop adjusting plate member 45 is positioned on the bolt members 26 and 27 by reason of spaced openings that are provided therein along the longitudinal medial line, adjacent the opposite ends thereof. A wing nut 46 is then threaded on each of the bolts 26 and 27 so that when the wing nuts 46 are loosened the support member 30 may be vertically adjusted in relation to the plate member 11, but when the wing nuts 46 are tightened, the support member 30 will be retained in fixed adjusted relation to the plate member 11.

A support or rear rest assembly 47 is provided for retaining the book and magazine holder 10 in vertical or inclined relation to a horizontal surface, as shown in FIG. 2. The support assembly 47 includes a pair of side bars 48 and 49 that have the upper ends thereof bent at

right angles thereto, as at 50 and 51, whereby the assembly 47 may be pivotally connected to the apertured ears 22 and 23 that extend rearwardly of the body plate member 11. A rubber foot member 52 being mounted on the opposite end of each of the side bars 48 and 49, and the foot members 52 in conjunction with the scuff member 21 will prevent the book and magazine holder 10 from sliding on any surface on which the book and magazine holder 10 is placed. Extending between and secured at its opposite ends to the side bars 47 and 48 is a cross bar 53, which is provided at its medial portion with an eye 54. A hook member 55 is pivotally connected to the eye 54, and the hook member 55 may be selectively inserted into the links of the chain 25 to retain the support assembly 47 in adjusted relation to the plate member 11.

The lower support member 18 is provided with a pair of openings 56 and 57 that are equally spaced from the medial portion of the lower support member 18 and eye-pins 58 and 59 are adapted to be removably inserted into the openings 56 and 57. A rubber band 60 is connected to and extends between the eye-pins 58 and 59 so that the rubber band 60 may engage and conform to the outline of the pages 61 of an open book 62, as shown in FIG. 4.

When the book and magazine holder 10 is to be used it is positioned on a suitable surface, as shown in FIG. 2, and the support assembly 47 is moved in relation to the body plate member 11 until the body plate member 11 is positioned in the proper inclined relation to a surface, as shown in FIG. 2, at which time the hook 55 is inserted in the nearest link of the chain 25 to retain the body plate member 11 in the desired position.

The bottom edges of the open book 62 are then placed on the lower support member 18 and the upper support member 32 is moved upwardly or downwardly as the situation requires so that the top edges of the open book 62 are positioned intermediate of the front flange 37 and intermediate plate member 31. The wing nuts 46 are then tightened to retain the upper support member 32 in the fixed adjusted position that is determined by the size of the book 62. The eye-pins 58 and 59 are then inserted into the openings 56 and 57 so that the rubber band 60 extends over the lower central portions of the pages 61 of the open book 62, as shown in FIG. 4.

The book 62 will, therefore, be positioned and retained at the inclination best suited to the reader and the pages 61 of the book 62 may be turned as needed.

There has thus been described a book and magazine holder that is versatile in use and may be made of metal, plastic or any other suitable material and it is believed that from the foregoing description the manner of assembling the book and magazine holder, as well as the use thereof, will be apparent to those skilled in the art.

It is also to be understood that changes in the minor details of construction, arrangement and combination of

parts may be resorted to provided they fall within the spirit of the invention and the scope of the appended claims.

Having thus described the invention what is claimed 5 as new and desired to be secured by Letters Patent is:

1. In a holder for books or the like, including an upright base, a bottom flange extending forwardly of said base and adapted to receive a book or the like thereon, an intermediate plate, means slidably connecting said 10 intermediate plate to said base for vertical adjusting movement relative thereto, and adjustable support means for varying the angle of inclination of said base and intermediate plate; the improvement comprising an inverted U-shaped page holder comprising a web formed with 15 front and rear depending flanges, said web extending across said intermediate plate above the same, said front and rear flanges straddling said intermediate plate forwardly and rearwardly thereof, a pair of laterally spaced pins connecting said front and rear flanges together, said intermediate plate being formed with a pair of laterally spaced 20 holes slidably receiving said pins therein to connect said page holder to said intermediate plate for forward and rearward movement relative thereto, and expansive spring means interposed between said intermediate plate and 25 said rear flange to load said page holder to a rearmost position.

2. A holder for books or the like according to claim 1, there being a lower page holder comprising rigid page 30 engaging means on said bottom flange in forwardly spaced relation to said base, a resilient band, said rigid means having means mounting said band in upwardly spaced relation to said bottom flange, and said rigid means comprising two laterally spaced elements, said elements being spaced apart a distance less than the width of an open 35 book seated on said bottom flange whereby to provide laterally spaced and rigid page engaging means with said band providing resilient page engaging means between said rigid page engaging means.

3. A holder for books or the like according to claim 1, 40 there being stop means interposed between said front flange and said intermediate plate to limit rearward movement of said page holder and to maintain said front flange in at least a minimum spaced relation to said intermediate plate.
